US0D1108288S

(12) **United States Design Patent** (10) Patent No.: **US D1,108,288 S**
(45) Date of Patent: ** Jan. 6, 2026

(54) **CLOCK FACE**

(71) Applicant: **Se Hee Hwang**, Seoul (KR)

(72) Inventors: **Se Hee Hwang**, Seoul (KR); **Won Young Kim**, Seoul (KR)

(**) Term: **15 Years**

(21) Appl. No.: **35/522,985**

(22) Filed: **Nov. 15, 2023**

(80) **Hague Agreement Data**

Int. Filing Date: **Nov. 15, 2023**

Int. Reg. No.: **DM/233942**

Int. Reg. Date: **Nov. 15, 2023**

Int. Reg. Pub. Date: **Nov. 15, 2024**
